UNITED STATES PATENT OFFICE.

MOSES G. HUBBARD, OF CHICAGO, ILLINOIS.

RAILROAD-TRACK.

SPECIFICATION forming part of Letters Patent No. 465,984, dated December 29, 1891.

Application filed November 7, 1890. Serial No. 370,660. (No model.)

To all whom it may concern:

Be it known that I, MOSES G. HUBBARD, a citizen of the United States, and a resident of Chicago, county of Cook, and State of Illinois, have invented a new and useful Improvement in Railroad-Tracks, of which the following is a full, clear, and exact description, reference being had to the accompanying drawings, making part of this specification.

10 My invention relates to certain improvements in the construction of railroad-tracks in which the rails are provided with lapping beveled ends; and it consists in the combination, with the rails, of fish-plates formed to utilize the lapped joint and give greater stiffness and rigidity thereto, and adapted to be rolled or pressed out of sheet-steel of uniform thickness in order to utilize the elasticity of the steel in a lateral direction to exert a continuous and permanent elastic force on the base of the rail and on the bolts and nuts, by which the plates are attached to the rail for preventing the parts from jarring loose, and with sufficient scope to the elasticity to take up all ordinary wear, and thereby to form a permanent and reliable attachment.

15 It further relates to the construction of the fish-plates, adapting them to be reversed when they become worn, and thereby to increase their durability.

20 In the accompanying drawings, Figure 1 is a transverse section through a rail, showing my improved double-flanged reversible fish-plates in end elevation. Fig. 1^a is a similar view showing the fish-plates as they appear previous to bolting the lower ends thereof together. Fig. 2 is a side elevation of the same, and Fig. 3 is a plan view showing, also, the beveled ends of the rail-sections united by said plates. Fig. 4 is a plan view of a rail composed of a short section cut from one end of a rail and united to the opposite end by a pair of my reversible fish-plates modified for that purpose to form a rail having squared ends from one which had beveled ends. Fig. 45 25 is a perspective view of the modified form of reversible fish-plate for use in side-track and switch construction; and Fig. 6 is a plan view showing a portion of main track secured as described, and a sliding-rail portion having its rail ends squared to adapt them to

slide by correspondingly squared ends for switches, &c.

A A' in Figs. 2 and 3 indicate adjoining end portions of two T-rails made of the usual or preferred form in cross-section, but having their ends provided each with the long bevel indicated at a and a', so that when two ends are brought together, as shown in Fig. 3, they will lap by each other on the bevel for some considerable distance between the double flanges of the fish-plates, by means of which the base of the rails is firmly clamped. By this construction the fish-plates (indicated at B and B') have each a solid rail-surface to rest against at a point opposite the joint or ends on the other side of the rail. The strain on the opposite fish-plates is at different points, and their leverage and the strength of the joint are greatly increased.

25 The double-flanged reversible fish-plates or splice-bars are made to fit the sides of the rail in the usual manner; but instead of the flanges terminating at the outer edge of the base of the rail they are extended around 75 said base in a half-round or U shape on each side, forming a double flange and terminating in pendent ribs b' and b', similar to the upper portion b b or splice-bars proper, and similarly provided with bolt-holes in such 80 manner that when the parts b b become worn or injured in any manner the fish-plates can be turned or reversed, the parts or ribs b' taking the place of the parts b b. This U shape of the sides, both internal and external, 85 is indispensable to the successful rolling of the fish-plates from thin steel, as any sharp corners would be fatal to the strength of the steel, and the elastic element aimed at cannot be so well attained with any other material. In fish-plates thus formed from thin sheet-steel of uniform thickness and curved as described, whereby all sharp angles are avoided, the elasticity of the steel is retained, and by forming them with the upper and 90 lower ribs set at an angle to each other or inclining outward from a common plane, as shown in Fig. 1^a, this elasticity is utilized for holding the bolts and nuts from jarring loose, for clamping tightly the ends of the rails, and 95 taking up wear, which would otherwise soon allow the parts to work loose. The lower ribs

give greatly-increased vertical stiffness or 5 rigidity to the joint, and it will be seen that when the upper portions or ribs $b\ b$ are drawn snugly against the rails the lower parts or 10 ribs $b'\ b'$ will stand flaring outwardly, and by drawing these inward toward each other and 15 into the vertical position shown in Fig. 1 by the supplemental bolts C' , similar to those at 20 C, uniting the parts b and the rail, they are 25 made to clamp the ends of the bases of the rails together snugly with a strong elastic 30 force and thereby give greatly-increased lateral stiffness to the joint and a continuous or 35 permanent elastic pressure on all of the bolts 40 and nuts sufficient to prevent their jarring 45 loose, which is important in the main track as it is not so frequently inspected as the 50 track at switches and stations. By the use 55 of these elastic fish-plates the necessity for 60 using elastic nut-locks or other devices for a 65 similar purpose is obviated.

In constructing the track with rails having 70 beveled ends, the use of the double-flanged 75 fish-plates described having the pendent ribs 80 would interfere with the free sliding movements 85 of the rails at switch-connections. To obviate this difficulty, a reversible single-flanged fish-plate having the modified 90 form shown at B^2 in Fig. 5 is employed at 95 30 such connections, the lower pendent ribs being dispensed with, leaving the lower flat 100 surface of the rail free to slide laterally. In 105 this construction of the fish-plates the base- 110 flanges conform exactly in shape to the up- 115 right part or fish-plate proper, and when the 120 latter becomes worn or injured the plates 125 may be reversed, using the side flanges, which 130 are suitably perforated, to take the place of 135 the upright part.

140 The fish-plates are formed, as stated, by 145 rolling or pressing them from sheet-steel of 150 uniform thickness into the form shown and 155 described, as from the peculiar form given to 160 them and the lap given to the rails (whereby 165 their leverage becomes favorable to the 170 strength and stiffness of the fish-plates) they 175 can be made from much lighter metal than 180 where the usual form of joint and fish-plate 185 is employed.

190 The reversible fish-plates should be made 195 with the portion intended to replace the worn- 200 out portion slightly wider than the space be- 205 tween the upper and lower flanges of a new 210 rail, so that when the rail is worn a tight fit 215 may be attained and the joint made as per- 220 fect as when new.

In Fig. 4 a rail formed with beveled ends is 225 shown with its ends squared by cutting a short 230 portion, as a' , from one end of the rail and 235 uniting or splicing it to the other end a by 240 means of the single-flanged fish-plates B^2 .

In Fig. 6, A and A' are rails of the main 245 track, having their joints secured by the 250 double-flanged fish-plates described, and G' 255 G' are siding-rails having square ends and 260 flat under surfaces to adapt them to the sur- 265 face of the cross-tie supporting them.

The squared ends of the last rails of the 270 main track and of the switch-rails may be 275 formed, as shown at K' K', by the cutting and 280 splicing, as shown above, of rails which had 285 beveled ends. In this way the necessity of 290 keeping on hand two kinds of long rails would 295 be avoided and would frequently be conven- 300ient for repairs.

K is one of the connecting-rods connecting 305 the switch-rails in the ordinary manner.

By the combination of the above-described 310 improvements and their modifications, as de- 315 scribed, a system of railroad-tracks may be 320 formed having the maximum degree of safety, 325 smoothness, durability, and convenience, with 330 a probable reduction in first cost, while the 335 expense of keeping it in repair would be ma- 340 terially reduced.

Having thus described my improved system 345 of railroad-tracks, what I claim as new, and 350 desire to secure by Letters Patent, is—

1. In a fish-plate rail-joint, the combina- 355 tion of T-rails having beveled ends and the 360 fish-plates for uniting said ends of a form 365 adapting them to be rolled from sheet-steel of 370 uniform thickness and to fit the sides of the 375 rail and embrace the base-flanges thereof, and 380 having the pendent flaring portions, adapting 385 them, when drawn into place by the retain- 390 ing-bolts, to exert a strong and continuous 395 lateral pressure on the wearing parts of the 400 joint, substantially as described.

2. A double-flanged splice-bar or fish-plate 405 having flanges inclined with respect to each 410 other and united in U shape and all the 415 corners of which are curved, as described, adapt- 420 ing said fish-plate to be rolled from sheet-steel 425 of uniform thickness and to retain the elas- 430 ticity of the metal, whereby it is adapted to 435 exert a strong elastic pressure on the rails 440 and on the retaining-bolts and nuts, substan- 445 tially as described.

3. A flanged fish-plate of uniform thickness 450 and of a form adapting it to be rolled from 455 sheet-steel and to be reversed in use and hav- 460 ing its upper and lower portions inclined or 465 set at an angle to each other, permitting the 470 lateral elasticity of the metal to be utilized, 475 for the purposes and substantially as de- 480 scribed.

4. In a rail-joint, the combination, with the 485 T-rails, of two reversible double-flanged fish- 490 plates of uniform thickness and of a form 495 adapting them to be rolled from sheet-steel, 500 and having the opposing upper and lower por- 505 tions inclined or made flaring with respect to 510 each other, whereby the lateral elasticity of 515 the metal is utilized when said plates are 520 bolted together, substantially as and for the 525 purpose described.

In testimony whereof I have hereunto set 530 my hand this 1st day of November, A. D. 1890.

MOSES G. HUBBARD.
